UNITED STATES PATENT OFFICE

2,687,515

SWIVEL PLUG ADAPTER

George W. Booth, Charleston, W. Va.

Application July 13, 1951, Serial No. 236,551

1 Claim. (Cl. 339—8)

1

This invention relates to swivel attachment plugs, and more particularly to a swivel plug adapter providing a swivel connection between an appliance cord and an electrical socket.

A main object of the invention is to provide a novel and improved swivel plug adapter which is simple in construction, which provides a continuous rotatable connection between the plug of an appliance cord and an electrical socket, and which involves only a few parts.

A further object of the invention is to provide an improved swivel plug adapter which is inexpensive to manufacture, which is sturdy in construction, which is compact in size, and which provides a rotatable mechanical connection between the plug of an appliance cord and an electrical socket, as well as providing electrical connections from the socket to said plug.

Further objects and advantages of the invention will become apparent from the following description and claim, and from the accompanying drawings, wherein:

Figure 1 is a side elevational view of an improved swivel plug adapter constructed in accordance with the present invention;

Figure 2 is a bottom view of the swivel plug adapter of Figure 1;

Figure 3 is a vertical cross-sectional view taken on the line 3—3 of Figure 1;

Figure 4 is a horizontal cross-sectional view taken on the line 4—4 of Figure 1;

Figure 5 is a horizontal cross-sectional view taken on the line 5—5 of Figure 1;

Figure 6 is a horizontal cross-sectional view taken on the line 6—6 of Figure 1;

Figure 7 is a horizontal cross-sectional view taken on the line 7—7 of Figure 1;

Figure 8 is a top plan view of the swivel plug adapter of Figure 1.

Referring to the drawings, the improved swivel plug adapter is designated generally at 11, and comprises a female plug receptacle 12 which is integrally molded with a post member 13 extending axially through the female plug member 12 and which contains a conductive core 14 of metal rod material. Surrounding the core 14 is the insulating sheath 15. The post member 13 extends a substantial distance below the bottom of the plug member 12 and has rigidly secured on its portion immediately sub-adjacent the female plug member 12 the metal sleeve 16. Designated at 17 and 18 are respective insulating discs which are rigidly secured to the bottom of the female plug member 12 between the metal sleeve 16 and the lower rim of the shell of said plug member

2

19. Designated at 19 is a first spring contact which is mechanically and electrically connected to the top rim of the sleeve 16, as by welding or brazing, and designated at 20 is a second spring contact which is mechanically and electrically connected to the core 14. The respective spring contacts 19 and 20 are located in the female plug element 12 and are disposed below respective slots 21 and 22 formed in the top wall of the female plug element for the reception of the prongs of a conventional male plug employed with the appliance cord to be connected to the adapter. When the male plug is inserted in the female plug element 12, the prongs of the male plug engage the respective contact springs 19 and 20 and establish electrical contact therewith.

As shown in Figure 3, the lower end of the metal core 14 extends below the bottom rim of the insulating sleeve 15, and is formed with a ball tip 23. Designated at 24 is a male plug element which is formed with an axial bore 25 containing a bearing element 26. The annular male plug element 24 is rotatably engaged around the post member 13 with the bearing element 26 rotatably engaging the metal sleeve 16, as shown in Figure 3. The male plug element 24 is provided with respective prongs 27 and 28 adapted to be inserted in a conventional electrical socket, such as a wall receptacle. Designated at 29 is a first conductor which is connected to the prong 28, as by a conventional binding post 30, and which extends through the body of the male plug element 24. The top end of the conductor 28 is formed into a substantially circular loop 31 which extends around the upper portion of the sleeve 16 and is in rotative electrical contact therewith. As shown in Figure 3, the bearing sleeve 26 is sufficiently reduced in height to define an annular recess between its top rim and the disc element 18 adapted to receive the contact loop 31 of conductor 29. Designated at 32 is a second conductor which is connected to the prong 27, as by the conventional binding post 33, and which is formed at its upper end with a loop 34 engaged around and in rotative contact with the neck portion of the exposed lower end of core 14 immediately above the ball tip 23. It will therefore be apparent that the prongs 27 and 28 are electrically connected to the springs 19 and 20 through the respective conductors 32 and 29 and the respective elements 14 and 16, the elements 14 and 16 being rotatable relative to the conductors 32 and 29. Thus, the male plug element 24 may swivel freely relative to female plug element 12 while maintaining electrical con-

tact between the contact springs 19 and 20 of the female plug element and the prongs 28 and 27 of the male plug element 24. The conductor 32 provides a mechanical connection between the ball tip 23 and the binding post 33, preventing the axial separation of the male plug element 24 from the female plug element 12.

It will further be apparent that the plug of an appliance may be engaged in the female plug element 12 and the adapter may be engaged in the conventional receptacle. The appliance cord of the device thus electrically connected to the wall socket may rotate freely without becoming twisted and without disturbing the electrical connection to the wall socket.

While a specific embodiment of an improved swivel plug adapter has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A swivel plug adapter comprising a female plug receptacle having a pair of contacts, a post member axially secured to said female receptacle and substantially coextensive therewith, said post

5 member comprising a conductive core and an insulating sheath surrounding said core, a conductive sleeve secured on said sheath, an annular male plug rotatably mounted on said sleeve and slidably received on the core, said male plug having a pair of prongs, said post member extending into said male plug and the end of the core extending beyond the end of the insulating sheath and being formed with a ball tip, said core adjacent said tip having a diameter smaller than the tip, respective conductors connecting the contacts of the female receptacle to said core and sleeve, and additional respective conductors connected to the prongs of the male plug and respectively rotatively engaged on and encircling the sleeve and on the core portion of reduced diameter adjacent said ball tip and arranged to secure the male plug against endwise separation from the female plug receptacle.
